Primary Examiner — Cynthia Ramirez*Assistant Examiner* — Xavier Marti-Santos(57) **CLAIM**

The ornamental design for a perm rod assembly as shown and described.

DESCRIPTION

FIG. 1 is an exploded front, right side, top perspective view of a perm rod assembly showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, left side, bottom perspective view thereof; and,

FIG. 9 is a rear elevational view thereof, shown in an assembled state.

The broken lines in the drawing depict portions of the perm rod assembly that form no part of the claimed design.
